UNITED STATES PATENT OFFICE.

EDMUND P. HAYES, OF WICHITA, KANSAS, ASSIGNOR TO HAYES EQUIPMENT MANUFACTURING COMPANY, OF WICHITA, KANSAS, A CORPORATION OF KANSAS.

DISPENSING APPARATUS.

Application filed June 13, 1928. Serial No. 285,147.

This invention relates to dispensing apparatus, and with regard to certain more specific features, to liquid dispensing apparatus for gasoline filling stations and the like.

Among the several objects of the invention may be noted the provision of an improved and simplified cylindrical reservoir construction wherein certain glass enclosing cylinders are rendered less subject to breakage; and the provision of a device of the class described including means for obtaining a quicker level of liquid prior to dispensing. Other objects will be in part obvious and in part pointed out hereinafter.

The invention accordingly comprises the elements and combinations of elements, features of construction, and arrangements of parts which will be exemplified in the structure hereinafter described, and the scope of the application of which will be indicated in the following claims.

In the accompanying drawings, in which is illustrated one of various possible embodiments of the invention,

Fig. 1 is a diagrammatic assembly view showing the general relationship of parts;

Fig. 2 is a vertical section taken through a reservoir, showing certain details; and

Fig. 3 is a detailed section of a foot valve.

Similar reference characters indicate corresponding parts throughout the several views of the drawings.

Referring now more particularly to Fig. 1, there is illustrated at numeral 1 a supporting framework for a lower bowl casting or reservoir end member 3. This framework also supports a double acting single cylinder reciprocating hand pump 5 whose discharge 40 communicates by way of a pipe 7 with a fill pipe 9 in the interior of said bowl 3 (see also Fig. 2). An adjustable edged overflow pipe 11 is also positioned on the interior of the bowl 3 and communicates with a connecting 45 overflow pipe 13 leading back to a main supply tank 15.

The tank 15 has its liquid supply in communication with the suction end of pump 5 by way of a line 17 at the lower end of which is positioned a foot valve 19. The foot valve is detailed in Fig. 3, where is shown a casing 21 containing a poppet valve 23 operable to open upwardly when the pump 5 effects a suction stroke and operable downwardly upon

return stroke of the pump. This foot valve is 55 adapted to prevent return of liquid to the tank 15. It will be understood that the pump 5 includes the usual suction and lift valves associated with such pumps which valves are also adapted to prevent return flow of liquid 60 to the tank 15.

The bowl 3 is also provided with a night drain pipe 25 which leads back into connection with the overflow pipes 11, 13. This night drain pipe 25 is provided with a valve 65 27. The bowl 3 furthermore has the usual hose connection 29.

One of the novel features of this invention regards the reservoir of which bowl 3 is a part. This liquid reservoir comprises said 70 bowl 3 having therein the fill and overflow pipes 9 and 11 respectively. Mounted on and in sealed relation with the bowl 3 is a glass cylinder or enclosing member 31. The glass cylinder surrounds the pipes 9 and 11. It is 75 held down on the bowl 3, not in the usual manner by a plurality of external tie rods, but by means of a central tension cylinder or pipe 33 surrounding the central supply pipe or fill pipe 9.

The cylinder 33 is screwed into the bottom of the bowl 3 and is provided with a screw cap 35 which pulls down on an end casting or end member 37, the latter engaging the upper edge of the cylinder or enclosing member 31. 85 A suitable closure 39 is provided over certain openings in the end casting 37. It is to be understood that the casting 37 does not engage the threads of pipe 33 but is longitudinally movable with respect thereto, whereby a clamping action may be effected by the cap 35 so as to hold the glass cylinder 31 between the end casting 37 and the bowl 3. A suitable sealing means is used between the casting 37 and the glass container 31. A 90 packing dam 41 is used within the cylinder 33 so that the clamping cap 35 is not depended upon for providing a gasoline seal.

The advantage of having the single tension member or pipe 33 instead of a plurality of tension members is that upon assembly, the skill of a workman in drawing up a plurality of studs evenly is not depended upon to prevent uneven pressure on the edge of the glass cylinder 31. Such uneven pressure has been found to be the cause of much cylinder breakage. A person by drawing up the cap 35 is enabled to automatically apply even

pressure all around the edges of the cylinder 31. Rods 43 are used for properly spacing a protective screen 45 and not for tension purposes as will be comprehended when it is seen that they have no draw nuts at their upper ends.

Beside the above improvements, the use of the pipe 33 effects other advantages. At its lower portions said pipe 33 is provided with openings 45 for permitting exit of incoming liquid from the fill pipe 9, whereby liquid enters the cylinder with a relatively undisturbed flow. Near its upper end the pipe 33 is provided with outlet openings 47 which are positioned an appreciable distance below the upper edge 49 of the fill pipe 9 and above the upper edge 51 of the overflow pipe 11. If valve leakage does occur in the present apparatus siphoning will be effected during the period that the liquid level descends to the level of the openings 47 and, as will be shown hereinafter, this effects certain advantages.

Heretofore descending pipes, sleeves and the like have been used to effect a gentle descent of liquid but they have been vented above the upper edge of the fill pipe so as to prevent a siphoning out of the cylinder when the pump stopped, the idea being had in mind that the pump and other valves associated with the fill pipe might leak.

As stated above I place the elevation of openings 47 between the edges of pipes 9 and 11. Hence after a filling operation with non-leaking pump and foot valves, the liquid level in the container drops down to the level of the edge 51 of pipe 11. The liquid level in the tube 33 will then stand at the same level as in the cylinder 31.

If the valves happen to leak, then a siphoning return action through pipe 9 takes place until the level of the liquid descends to the level of the openings 47. Hence it will be seen that the excess liquid has two exits from the container, one through the overflow and the other by siphoning through the fill pipe 9, thereby shortening the time in which it takes to reach the proper level of the elevation of the edge 51 of the pipe 11.

Heretofore the positioning of the vent above the edge 49 of pipe 9 also resulted in sideward spouting of fluids through the vent due to the spreading action of the stream but my openings 47 are positioned at points where the liquid has a natural downward travel and does not tend to spurt out. The arrows in Fig. 2 indicate how the liquid passes the opening without a tendency to spurt violently through them. This improved feature has resulted in the elimination

of a deflector member which was heretofore required to reduce the spouting action.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawings shall be interpreted as illustrative and not in a limiting sense.

I claim:

1. In a liquid dispensing device, a reservoir comprising end members, an enclosing member therebetween, a fill pipe located centrally with respect to said members and means for clamping said enclosing member between the end members comprising a tension pipe spacedly surrounding said fill pipe. 75

2. In a liquid dispensing device, a reservoir comprising end members, an enclosing member therebetween, a fill pipe located centrally with respect to said members and means for clamping said enclosing member between the end members comprising a tension pipe spacedly surrounding said fill pipe and openings in said tension pipe below the upper edge of the fill pipe. 85

3. In a liquid dispensing device, a reservoir comprising end members, an enclosing member therebetween, a fill pipe located centrally with respect to said members and means for clamping said enclosing member between the end members comprising a tension pipe spacedly surrounding said fill pipe, an overflow pipe in the reservoir having a lower edge than the edge of the fill pipe and openings in said tension pipe below the upper edge of the fill pipe and above the upper edge of said overflow pipe. 95

4. In a liquid dispensing device, a reservoir comprising end members, an enclosing member, therebetween, a fill pipe located centrally with respect to said members and means for clamping said enclosing member between the end members comprising a tension pipe spacedly surrounding said fill pipe, an overflow pipe in the reservoir having a lower edge than the edge of the fill pipe and openings in said tension pipe below the upper edge of the fill pipe and above the upper edge of said overflow pipe and other openings in said tension pipe below the edge of said overflow pipe. 100 110 115

In testimony whereof, I have signed my name to this specification this 8th day of June, 1928.

EDMUND P. HAYES.
